[57] CLAIM

The ornamental design for a linkage for swingably supporting a loadbearing member on a vehicle, as shown and described.

DESCRIPTION

FIG. 1 is a top left perspective view of a linkage for swingably supporting a loadbearing member on a vehicle, showing my new design;

FIG. 2 is a bottom right perspective view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and

FIG. 8 is a front elevational view thereof.

FIG. 2

FIG. 4

FIG. 5

FIG. 6

FIG. 7

FIG. 8
